(57) **CLAIM**

The ornamental design for a partition with transparent display as shown and described.

DESCRIPTION

FIG. 1 is a front, right, top perspective view of a partition with transparent display showing our new design;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom plan view thereof;

FIG. 8 is a cross-sectional view taken along line 8-8 in FIG. 2;

FIG. 9 is an enlarged detailed view of the boxed area 9 in FIG. 8; and,

FIG. 10 is a perspective exploded view of a partition with transparent display.

The dash-dash broken lines show portions of the article that form no part of the claimed design. The dot-dot-dash broken lines shown in FIGS. 8 and 9 illustrate the border of the enlarged detailed view and form no part of the claimed design.

1 Claim, 10 Drawing Sheets
